UNITED STATES PATENT OFFICE

HARPER A. BUSBY, OF INDIANAPOLIS, INDIANA

SASH HOLDER

Application filed May 17, 1929. Serial No. 363,764.

This invention relates to a sash-holding device to be employed with a window sash and frame in place of the usual cord and weights for maintaining the window in a given position. With this device no weight chamber is necessary in the window frame, hence a great saving in space is accomplished. Another advantage gained is the fact that no space is provided for the accumulation of dust to be blown about when a sash cord is replaced. The absence of the window weights reduces the weight of the complete window assembly, a feature of great importance particularly for motor vehicles and in ship building where weight is an important factor.

The principal object of the invention is to provide a device of the character described which will be an improvement over that disclosed in my prior Patent No. 1,553,306, issued September 15, 1925.

The principal feature of the invention resides in the provision of a pair of members having depressions in one which are engaged by correspondingly spaced projections in the other, the said members being mounted respectively on the window frame and on the sash. One of said members is yieldingly mounted so that the depressions and projections engage with sufficient force to overcome the tendency of gravity to lower the window but at the same time permit movement thereof by hand.

Another feature of the invention resides in the provision of projecting portions on one of said members which are used as guideways for the window sash to prevent rattling and to form a weather stripping.

The full nature of the invention and other objects and features thereof will be fully understood from the accompanying drawings and the following descriptions and claims:

In the drawings Fig. 1 is an elevational view of a portion of a window frame and window sash with parts cut away to show the invention in detail. Fig. 2 is a horizontal cross section taken on the line 2—2 of Fig. 1. Fig. 3 illustrates a modified form of the device shown in similar cross section to Fig. 2. A window frame 10 is here shown as a

solid member having no chamber therein for the usual window weights and cords. Associated therewith is a window sash 11 having a window pane 12. The sash is held in place by the usual projecting portion 13 of the window frame and the usual waling strip 14.

Fastened in the groove between the portion 13 and the waling strip 14 of the window frame is a channel-shaped member 15 having arcuate depressions 16 in the web thereof. The member 15 preferably extends the whole height of the window frame 10 and is fastened thereto by means of screws 17 inserted through counter-punched holes in the web of the said member. The legs of the channel-shaped member 15 engage mortices 18 provided in the window sash and act as a guide for said sash to prevent rattling and also act as weather stripping to prevent the passage of air about the window.

A metallic strip 19 has fastened thereto a plurality of cylindrical members 20 positioned within cylindrical recesses in the window sash. Certain of the members 20 are surrounded by helical springs 21 abutting at one end against the member 19 and at the other against the inner end of the aforesaid cylindrical recesses. The member 19 carries arcuate projections 22 of the proper spacing and proper dimensions to engage the arcuate depressions 16 of the member 15. The engagement of the projections 22 and the recesses 16 is maintained by the springs 21 and the springs are so graduated that the weight of the window is not sufficient to break the said engagement, but the manual application of a small additional force will be sufficient to raise and lower the window.

In the construction herein shown the portion of the device carried upon the window sash is shown located adjacent to the lower edge of the sash. A similar construction is preferably positioned near the upper edge of the sash and both sides of the sash are similarly equipped.

Several modifications of the structure herein shown are possible without departing from the broader aspect of the invention. For example, the channel-shaped members

may be placed on the window sash and the yieldingly-mounted members may be placed on the window frame. The arcuate depressions and projections may be in the reverse relation to that shown herein and need not be of the exact arcuate form illustrated. The only function of the projections and depressions is to support the window against the force of gravity. For this function it is only necessary that the lower portion of each projection and depression be shaped to engage at the proper angle. The shape of the upper portion of each projection and depression is immaterial except that they should offer a minimum resistance to raising the window. If the weather stripping and guide feature is not desired, the channel-shaped members 15 may be replaced by a simple plate carrying appropriate projections or depressions.

Fig. 3 illustrates other modifications of the device, wherein the channel-shaped member 15 is replaced by an L-shaped member 115 engaging a single mortice 118 in the window sash. The member 115 has depressions similar to the depressions 16 in member 15 and is herein shown covered with a coating of rubber 123 or other resilient material for noiseless operation. A roller 124 pivotally mounted in a yoke member 125 engages the rubber coating 123 and is yieldingly associated with the window sash 11 by means of spring 121 as disclosed in my prior patent aforesaid. In this construction the roller 124 may be considered as the projecting portion of the yieldingly mounted member in the same manner as portions 22 previously described.

The invention claimed is:

- 40 1. The combination with a window sash member and window frame member, of an element secured to one of said members and having a portion closely engaging a mortice in the other of said members, and a yieldingly-mounted element carried by said last-mentioned member, said elements having corresponding projections and depressions shaped for yielding engagement.
- 45 2. The combination with a window sash member and a window frame member, of a channel-shaped element secured to one of said members and having portions closely engaging mortices in the other of said members, and a yieldingly-mounted element carried by said last-mentioned member, said elements having corresponding projections and depressions shaped for yielding engagement.
- 50 3. The combination with a window sash member and a window frame member, of a metallic element secured to one of said members and having a portion closely engaging a mortice in the other of said members, a metallic strip associated with the other of said members, elements attached to said sec-

ond strip and receivable in recesses in its associated window member, and yielding means interposed between said strip and its associated member, said strip and said metallic element having corresponding depressions and projections for yielding engagement.

4. The combination with a window sash and a window frame, of a metallic element secured to said window frame and having a portion closely engaging a mortice in said window sash, a metallic strip associated with the said sash, elements attached to said strip and receivable in recesses in the said sash, and yielding means interposed between said strip and said sash, said strip and said metallic element having corresponding depressions and projections for yielding engagement.

5. The combination with a window sash and a window frame, of a channel-shaped element secured to said window frame and having portions closely engaging mortices in said sash, a metallic strip associated with said sash, elements attached to said strip and receivable in recesses in the said sash, and yielding means interposed between said strip and said sash, said strip and said channel-shaped element having corresponding depressions and projections for yielding engagement.

In witness whereof, I have hereunto affixed my signature.
